UNITED STATES PATENT OFFICE.

WAYNE P. ZENT, OF TROY, NEW YORK.

LINOTYPE MATRIX.

Application filed July 18, 1917. Serial No. 181,186.

To all whom it may concern:

Be it known that I, WAYNE P. ZENT, a citizen of the United States, residing at Troy, county of Rensselaer, and State of 5 New York, have invented certain new and useful Improvements in Linotype Matrices, of which the following is a specification.

Reference may be had to the accompanying drawings, and the reference characters 10 marked thereon, which form a part of this specification. Similar characters refer to similar parts in the several figures therein.

This invention relates to various kinds 15 of typographical-character-bearing units, such as logotypes, type-blocks, type-bars and linotypes, and dies or matrices for use in the production of the same.

The principal object of the invention is to facilitate preparing a form for printing 20 tabular matter, and particularly numerical tabular matter in columns.

Other objects will appear in connection 25 with the following description.

In the drawings I have shown the invention applied to a font of line-casting matrices, such showing being merely illustrative, as for certain purposes of the invention it is equally applicable to various other 30 kinds of typographical-character-bearing units.

Fig. 1 of the drawings is a view in perspective showing several line-casting matrices assembled, illustrating certain features of my invention.

35 Fig. 2 is a view in perspective of a linotype or type-bar formed by said assembled matrices.

Fig. 3 is a view in perspective of one of the matrices shown in Fig. 1.

40 Fig. 4 is a view similar to Fig. 1, showing matrices bearing various other typographical characters, illustrating certain other features of my invention.

Fig. 5 is a view in perspective of a linotype 45 or type-bar formed from the matrices as assembled in Fig. 4.

Fig. 6 is a view in perspective of one of the matrices shown in Fig. 4.

Fig. 7 is a view in perspective of a single 50 matrix bearing various other typographical characters.

Fig. 8 is a view in perspective of a single matrix having a single molding-face.

55 Fig. 9 is a view in perspective of a linotype or type-bar formed by assembling together the matrices shown in Figs. 1 and 4.

In the application of the invention to line-casting matrices, for certain purposes of the invention it is immaterial whether said matrices have severally a single molding-face 60 or a plurality of molding-faces. I prefer to employ matrices having severally a plurality of molding-faces for the reason among others, that by so doing I can greatly reduce the number of matrices to be employed. 65

Referring to the drawings, I have shown in Figs. 1 and 3, four matrices, 4, 4^a, 4^b, 4^c, each having two molding-faces, 6 and 6^a, respectively.

Certain of these matrices severally bear 70 on one of said molding-faces, a plurality of numerical typographical characters, as illustrated by the numbers, "12" and "50" on the molding-face, 6, of the respective matrices, 4 and 4^b, said numbers "12" and "50", being 75 merely illustrative of any desired plurality of typographical characters. Said plurality of characters are grouped on the respective molding-face of the matrix, side by side adapted for simultaneous use and they are 80 adapted in use to aline in column-form respectively with the typographical characters on other matrices in the front, which severally bear a plurality of typographical characters arranged side by side upon a 85 common molding-face.

Thus as shown in Fig. 1, the numeral, "2", on the matrix, 4, alines in column-form with the "0", on the matrix, 4^b, and the numeral, "1" on the matrix, 4, alines in column-form 90 with the numeral, "5" on the matrix, 4^b.

Certain of the molding-faces on the matrices comprising a font bear but a single typographical character located to aline in use in column-form with one of the typographical characters on the several matrices 95 which bear a plurality of such characters on a common molding-face.

Thus as shown in Fig. 1 the molding-face, 6, of the matrix, 4^a, bears the numeral, "3", 100 located to aline in column-form with the numeral, "2", on the matrix, 4, and with the "0" on the matrix, 4^b, and the molding-face, 6^a, on the matrix, 4^c, bears the numeral, "7", located to aline in column-form with 105 the numeral, "1", on the matrix, 4, and the numeral, "5", on the matrix, 4^b, said numerals "3" and "7", being illustrative of any desired single typographical characters.

As shown in Fig. 1, the matrices, 4, 4^a 110 and 4^b, are shown with their respective molding-faces, 6, in casting position while

the matrix, 4^e, is shown with its molding-face, 6^a, in casting-position.

As thus assembled said matrices will produce a linotype or type-bar, 8, as shown in Fig. 2, having in column-form, reading transversely of its edge, lines of typographical characters, the first and third of said lines bearing in type-form the characters, "1 2" in column alinement with the respective characters "5 0," while the second and fourth lines bear in type-form the character, "7," in column alinement with said characters, "1" and "5," and the character, "3," in column alinement with said characters, "2" and "0," thus forming an improved linotype which constitutes a part of my invention.

The several molding-faces on the several matrices of a font of matrices embodying my invention, may be provided with any desired typographical characters arranged in the manner above described, the several molding-faces bearing either a single character or a plurality of characters.

I have shown on the molding-face, 6^a, of the matrix, 4, the multiplication sign "×" in a position corresponding with that of the numeral "3" on the molding-face, 6^a of the matrix, 4^a, and the same multiplication sign "×" on the molding-face, 6^a, of the matrix, 4^b, in a position corresponding with that of the numeral "3" on the molding-face, 6^a, of said matrix, 4^a, whereby said multiplication signs are adapted to aline in column-form with the respective individual characters on the other matrices respectively. Said multiplication signs are merely illustrative of various typographical characters, which may be so employed, such as punctuation marks, fractions, reference characters, etc., used in printing.

I have shown in Fig. 4, matrices, 4^d, 4^e, and 4^f, similar to those above described bearing upon each molding-face a plurality of typographical characters, one of which is a numerical character, while the other is a rule, 9.

Said rules, 9, preferably extend transversely of the respective matrices and from edge to edge thereof, being adapted for alinement in vertical or column-form with the similar rules on other matrices in the font, whereby, when the matrices are assembled, said rules form a substantially continuous rule-matrix which forms upon the linotype or type-bar a printing rule, 9^a, which is in fact continuous and which is cast integral with the other typographical characters on the linotype or type-bar, 10, extending longitudinally of the edge of the linotype or type-bar, as shown in Fig. 5, thus forming an improved linotype which constitutes a part of my invention.

I have shown the rules, 9, on the molding-faces, 6, located at the left of the adjacent

numerical characters, while the rules on the molding-faces, 6^a, are placed at the right of the adjacent numerical characters.

The rule-characters on the rule-forming matrices are so placed that they are in column-alinement with the respective single numerical characters on other molding-faces whether such single numerical characters are on molding-faces bearing one character only or on molding-faces bearing a plurality of numerical characters.

The same two characters thus appear side by side on one molding-face, and side by side in reverse order on the other molding-face of the same matrix, requiring operation of but a single key of the linotype machine (not shown) to deliver said characters in either order of arrangement, the particular order being determined by the casting-position of the matrix.

The numerical characters shown on the matrices in Fig. 4 are illustrative of any typographical characters which it may be desired to employ.

While I have shown the typographical characters arranged to read longitudinally of the respective matrices and transversely of the respective linotypes cast therefrom, I do not wish to be limited to such arrangement, as for certain purposes of the invention it is immaterial whether they be arranged in said manner, or whether they be arranged to read transversely of the respective matrices, and longitudinally of the respective linotypes. Either of said arrangements may be employed in a font of matrices embodying my invention depending upon whether it is desired to cast vertical linotypes or horizontal linotypes.

A further feature of my invention consists in making the molding-faces on a font of matrices each em-square, whether bearing a single character or a plurality of characters.

The linotypes produced by assemblages of such matrices are thus uniformly of em-width, and are an exact number of ems in length without the use of space-bands or other justifying devices; and the form made up from such linotypes is always an exact number of ems in width, as well as an exact number of ems in length, and the characters in such a form can be accurately alined both longitudinally and transversely thereof.

By the term "font" I mean a series consisting of any desired number of matrices or other typographical-character-bearing units sufficient for the work contemplated.

What I claim as new and desire to secure by Letters Patent is—

1. A font of line-casing matrices each having an em-square molding-face certain of said molding-faces severally bearing a plurality of numerical characters side by

side, certain other of said molding-faces severally bearing a vertical rule in column-alinement with one of said plurality of numerical characters.

5. 2. A font of line-casting matrices each having an em-square molding-face certain of said molding-faces severally bearing a plurality of numerical characters side by side, certain other of said molding-faces 10 severally bearing a single numerical character in column-alinement with one of said plurality of numerical characters and side by side therewith a vertical rule in column-alinement with another of said plurality 15 of numerical characters.

3. A font of line-casting matrices each having an em-square molding-face certain of said molding-faces severally bearing a plurality of numerical characters, certain 20 other of said molding-faces severally bearing single numerical characters in column-alinement with the respective single characters forming said plurality of characters,

certain other of said molding-faces bearing each a vertical rule in column-alinement 25 with the respective single numerical characters on other molding-faces.

4. A font of line-casting matrices each having an em-square molding-face, certain of said molding-faces severally bearing 30 a plurality of numerical characters, certain other of said molding-faces severally bearing single numerical characters in column-alinement with the respective single characters forming said plurality of characters, 35 certain other of said molding-faces bearing each a vertical rule in column-alinement with the respective single numerical characters on other molding-faces, and side by side therewith another typographical character in column-alinement with single numerical characters on other molding-faces.

In testimony whereof, I have hereunto set my hand this 16th day of July, 1917.

WAYNE P. ZENT.
